UNITED STATES PATENT OFFICE.

JOHN W. DUNLAP, OF MODESTO, CALIFORNIA.

DESIGN FOR A DIRECTION-SIGNAL CASING.

Application filed October 30, 1926. Serial No. 19,545. Term of patent 14 years.

To all whom it may concern:

Be it known that I, JOHN W. DUNLAP, a citizen of the United States, residing at Modesto, in the county of Stanislaus and State of California, have invented a new, original, and ornamental Design for a Direction-Signal Casing, of which the following is a specification, reference being had to the accompanying drawing, forming part thereof, and in which—

Fig. 1 is a rear end view of a direction signal casing, showing my new design, and Fig. 2 is a side elevation of the casing.

I claim:

The ornamental design for a "direction signal casing," as shown.

JOHN W. DUNLAP.
